ELEVATOR SAFETY DEVICE

William J. Martin, Buffalo, N. Y.

Application August 11, 1931, Serial No. 556,372

12 Claims. (Cl. 187—31)

This invention relates to a device associated with an elevator which is moved vertically in an elevator well having doors at one or more floors,— the safety feature of the device being that the elevator cannot be moved unless every one of the doors is closed. In particular, the invention relates to an elevator system in which the doors at each floor are of the dual, interconnected type and move toward each other to close their companion doorway.

One of the objects of the invention is to provide a reliable and inexpensive device which enables a single electric switch, located in the pent house of the building, to be actuated by any one of the various doors at the different floors.

Another object of the invention is to lock each companion pair of dual doors to each other when in their closed position so that the position of both determines whether or not electric current is to be allowed to flow to the elevator motor.

A further object of the invention is, in a case of emergency, to allow ingress into the elevator well even though every door be locked on the inside.

Numerous other objects of the invention and practical solutions thereof are disclosed in detail in the herein patent specification wherein, in the accompanying drawings:

Figure 1 is a diminutive, fragmentary, vertical section through an elevator well and associated parts showing the same equipped with my new safety device.

Figure 2 is a similar vertical section but taken at right angles to Fig. 1 on line 2—2, Fig. 1.

Figure 3 is a fragmentary, vertical section through an elevator well and associated parts showing a modified form of the invention as applied to single, sliding doors and showing such a door in its open position.

Figure 4 is an enlarged, fragmentary, horizontal section of the master switch taken on line 4—4, Fig. 3.

Figures 5 and 6 are enlarged, vertical sections through said master switch taken on correspondingly numbered lines of Figs. 4 and 3.

Figure 7 is an enlarged, vertical, longitudinal section through said master switch taken on line 7—7, Fig. 6.

Figure 8 is a fragmentary, enlarged front elevation of the dual door locking apparatus shown in Figs. 1 and 2.

Figure 9 is a horizontal section thereof taken on line 9—9, Fig. 8.

Figure 10 is a fragmentary, enlarged horizontal

section through a portion of the dual door locking apparatus taken on line 10—10, Fig. 8.

Figure 11 is a fragmentary, enlarged, vertical section through said door locking apparatus taken on line 11—11, Fig. 8.

Fig. 12 is a diminutive, schematic vertical section of elevator well showing the complete assembly of my invention with the rest of the elevator apparatus.

In the following description, similar characters of reference indicate like parts in the several figures of the drawings.

My invention may be embodied in various forms and in elevator safety devices of different constructions, and the present applications are therefore to be regarded merely as a small number of the possible organizations which come within the scope of my invention and satisfactorily carry out the function of same in practice. As here shown, the same is constructed as follows:

The numeral 20 represents one of the four vertical walls of an elevator shaft or well 21 in which is arranged a conventional, vertically-movable freight elevator 13 supported upon an elevator cable 14. The latter is vertically actuated from a conventional cable drum 15 driven through worm or other gearing 16 by an electric elevator motor 17. This electric motor is in series with a pair of switches, the one, 18, of which is manually actuated by the elevator operator and is located in the elevator, while the other switch is automatic in its operation and is arranged at the outer end of the drum 35, as hereinafter to be described. The electric power, which passes in series through said manual and said automatic switch and thence to the elevator motor 17, is derived from a conventional source of power 19.

The elevator well 21 is provided with a number of doorways 22 at the different floor levels 23. Each of said doorways is adapted to be either closed or opened by a pair of dual doors consisting of an upper or primary door 24 and a lower or secondary door 25. Each companion pair of dual doors is arranged in the usual and well known manner (not necessary to be here shown) whereby the force imparted to either open or close any certain primary door 24 is in the same measure transmitted to, and in a corresponding direction with, its companion secondary door 25. This relative direction of movement of said doors is indicated by arrows in the several views.

Arranged at the upper end of the elevator well

21 is the usual roof 26 of the building upon which is located a conventionalized pent house 27. Located within said pent house and suitably secured to a base plate 28 are a pair of uprights 5 or standards 30 and 31 in which is rigidly mounted a horizontal screw 32 the one end of which is, however, unthreaded. This screw is prevented from rotating by reason of suitable set screws 33 and 34 threaded through the standards 30 10 and 31 and bearing with their inner ends against the periphery of said screw. Longitudinally and slidably mounted upon said screw 32 is a wide faced drum 35 the front end of which is coaxially provided with an internal screw thread 15 which engages with the external screw thread of the screw 32. The rear end of said drum is reamed out at 36 so as to be a running fit on the smooth or rear end of said screw 32. By this construction the whole drum 35 is caused 20 to move longitudinally forward or backward as it is rotated in the one or other direction.

Secured by flat headed machine screws 37 to the front vertical end face of the drum 35 is an electrical insulating disk 38 which is constructed of fiber, synthetic resin or other similar insulating material. This insulating disk 38 25 is segmentally cut out to receive with a flush fit, a metallic segment 40 which is secured to said insulating disk by a number of shallow machine 30 screws 41. Longitudinally and slidably arranged in the front drum standard 30 are a horizontally disposed pair of electrical plungers or switch contacts 42, the outer ends of which are connected to electrical lead wires 43 which convey 35 the electrical current in series through the various electric apparatus (motor, elevator switch, relays, etc.) whereby the operator is enabled to cause the elevator to move up or down in the elevator well 21. The only important matter to 40 be here noted is that the switch contacts 42 and metallic segment 40 and associated parts constitute a master switch which when closed permits the elevator motor to receive electrical energy but which, when open, absolutely prevents 45 said elevator motor from receiving electrical energy irrespective of the position of the other switches, relays, etc.

These switch contacts are suitably insulated from the front standard 30, and each is resiliently urged rearwardly by a companion compression spring 44. The longitudinal, rearward movement of each of said switch contacts 42 is, however, definitely restricted by means of a stop collar 45 which is preferably formed integral with 50 its companion switch contacts and which, in its rearmost position, bears against the bottom of the coaxial, longitudinal, horizontal hole that receives its companion compression spring 44. The consequence of this construction is that, as the 55 drum 35 is rotated, the switch contacts 42 are caused to first break electrical contact with the metallic segment 40, the springs 44 in the meantime causing said contacts to maintain an electrical contact and the stop collars 45 not yet 60 having struck bottom during the thus far small recession longitudinally of the entire drum. Any electrical arcing which does occur when the current is broken is entirely confined to the one end of the segment 40, and this end is remote from 65 the area touched by the switch contacts 42 when the doors are all fully closed. Hence, what arcing does occur cannot cause a pitting of the actual points of effective electrical contact. At this time, however, the rear ends of said switch contacts 70 75 42 are still in contact with the front end of said

drum 35 so that if a considerable portion of water or dirty oil is present a certain amount of electrical energy might still flow through the master switch. To eliminate any possibility of such an electrical leakage, the ratio of drum 5 diameter to door movement is such that after the metallic segment 40 moves past the end of one of the switch contacts 42, the drum continues to rotate until it has moved longitudinally sufficiently rearward so that there is an actual air gap 10 between said switch contacts 42 and the front end of the drum 35, thereby positively ensuring that, when the doors 24, 25 are open, absolutely no current can be fed to the elevator motor.

A control cable 46 is secured by a cleat 47 to the 15 periphery of the drum 35 and is given a few turns around said drum at opposite sides of said cleat. The outer end of said control cable passes downwardly from said drum and is secured to a weight 48 which at all times tends to rotate said 20 drum so as to move the same longitudinally forward and thereby to close the electrical circuit through the switch contacts 42. Secured by bolts 50 to the secondary door 25 is an arm 51 which is bored vertically to receive the rear, downwardly 25 hanging end of the cable 46, said rear end continuing down around a suitable take up pulley 52 (which is pivoted to the stationary footing 53 of the elevator well 21) and thence passes up and is secured to the lower end of aforesaid weight 48, 30 thereby completing the circuit of said control cable.

Secured in the usual and well known manner to said control cable 46 by means of clamping screws 54 (see Figs. 8, 11 and 2) is a cable clip 35 55 the upper square end of which is adapted to bear against the lower flat face of the arm 51 of the secondary door 25. Thus, when said secondary door is lowered (opened), the clip 55 is pushed downwardly thereby rotating the drum 35 40 and opening the circuit through the master switch, i. e., through the switch contacts 42 and thus also opening the circuit through the motor which drives the elevator.

It is to be recalled that the primary and secondary doors 24 and 25 move in synchronism with respect to each other, being interconnected so that when the upper door 24 raises, the lower door 25 is depressed. Ordinarily the operator applies manual force to the upper or primary door 50 24 while the lower door is caused to open by the force derived from the movement of said primary door. Means are provided for locking the primary or upper door to the secondary or lower door so that neither door can be moved 55 until a suitable trip lever 56 is actuated. The arrangement by which these two doors are locked together is constituted as follows:

Secured to the upper face of the arm 51 of the secondary door 25 is a cylindrical, vertical guide 60 57. Vertically slidably within the bore of said guide 57 is a locking plunger 58 which is limited in its upward movement relatively to said arm 51 by the provision of a stop collar 60 which is screwed upon its lower end. The upper end of 65 said plunger 58 is provided with a conical head 61 which tapers upwardly and inwardly. The plunger is bored longitudinally and coaxially to give a loose sliding fit on the control cable 46, while the upper part of the clip 55 is coaxially 70 and downwardly recessed to very loosely receive the stop collar 60 of said plunger, the depth of said recess being such that, with the parts in the locked position of Figs. 8-11, there is a sizeable 75 clearance space between the top of the stop

collar 60 and the bottom of the guide 57. It will be noted that, in this position, the top of said clip 55 is in contact with the bottom face of the arm 51.

5 The primary or upper door 24 is provided with a laterally or outwardly projecting arm 62 secured to said door by bolts 63 or otherwise. Said arm 62 is vertically drilled to receive the locking plunger 58, the drilled hole having sufficient diameter to allow the conical head 61 of said plunger to pass easily therethrough. Fulcrumed at 64 upon the primary door 24 is the aforementioned trip lever 56, the same being vertically guided within the vertical slot 65 of a guide bracket 66 and a suitable handle 67 being provided to facilitate its manipulation by the operator of the elevator. The outer end of said trip lever terminates in a depressing tongue 68 which is adapted to bear downwardly against the upper inner end of a releasing lever 70. The latter is horizontally pivoted at 71 to a base block 72 which is suitably secured by welding or otherwise to the upper face of the arm 62. This releasing lever 70 at its outer end rises up above its supporting block 72 and then extends outwardly in an approximately horizontal direction to form a lifting tongue 73.

20 A base block 720 is secured to the upper face of said arm 62, similarly to the block 72. Pivoted at 71 and 710 to and situated between said base blocks 72, 720 is a pair of locking dogs 74 which are provided with lifting pins 75 and 750. These pins project out horizontally and laterally from one side of their companion dogs and rest upon the upper flat edge of the hereinbefore described lifting tongue 73.

Operation

25 The primary and secondary doors 24 and 25 are shown in the various figures in their closed position. To open the same the operator of the elevator lifts the handle 67 of the trip lever 56 and partially rotates the same in a vertical plane about its fulcrum 64. This moves downwardly the depressing tongue 68 of said trip lever and this movement in turn is imparted in a downward direction to the inner end of the releasing lever 70 which partially rotates about its pivot 71 and causes its outer end or lifting tongue 73 to be raised. This movement in turn is imparted in an upward direction to the lifting pins 75, 750 which tends to cause the locking dogs 74 to move upwardly and outwardly away from each other. It is to permit this movement that a certain clearance space is provided between the top of the stop collar 60 (of the locking plunger 58) and the bottom of the vertical guide 57. Further movement of said locking dogs causes their noses to be entirely disengaged from the lower annular shoulder of the conical head 61 of said locking plunger 58. The upper and lower doors 24, 25 are now unlocked from each other and the operator is able to lift the upper or primary door 24 and this movement in the usual and well known manner is imparted to the lower or secondary door 25 to depress the same.

30 This downward movement of the lower or secondary door 25 causes the lower face of its arm 51 to bear down upon the upper face of the cable clip 55 and the latter, being adjustably secured to the control cable 46, causes the drum 35 in pent house 27 to be rotated and retracted. The first part of this movement causes the metallic segment 40 to be rotated out of register with the switch contacts 42 thereby breaking the electric-

5 cal circuit through the electrical lead wires 43 and through the elevator motor. This action also confines any electrical arcing action to the extreme edge of said segment 40. Further rotation and retraction of said drum causes its outer face to be moved entirely out of contact with said switch contacts 42 (see Fig. 3) by reason of the stop collars 45, thereby absolutely cutting off any possibility of current flow even though the drum face be dripping with oil or water.

10 The elevator doors are now open and the elevator is either loaded or unloaded as the case may be. While this operation is going on all the other doors are prevented from being opened by unauthorized persons by reason of the fact that all 15 of said doors are locked together by means of the dogs 74 and these can only be unlocked by a manipulation of the trip lever 56 which is located interiorly of the elevator well.

20 When the loading or unloading of the elevator has been completed at any certain floor level, the operator merely closes the doors 24, 25 at that level. This movement automatically permits the weight 48 to wind the drum 35 upon the screw 32 so as to rotate the same and move it longitudinally back to the position shown in Figs. 1, 2, 4-7, thus permitting the flow of current through the switch contacts 42 of the master switch so that the elevator operator is free to supply current to the elevator motor by a manipulation of 30 his elevator cage rheostat or other electrical control apparatus.

25 If the operator should faint, or if for any other reasons it is necessary to gain access to the elevator well 21 from the outside, with all the doors 35 locked from the inside, special emergency or auxiliary means of unlocking at least one of the elevator doors is required. In the present invention this auxiliary means consists of a special key 76 (Figs. 8 and 9) which may be inserted from 40 the outside of the elevator well 21 through a key hole 77 so that its shank lies within a hollow groove 78 of a thrust block 80, the latter being suitably secured to one of the primary doors 24 by wood screws 81 or otherwise. By turning this 45 key 76, the trip lever 56 is caused to be moved in precisely the same manner as when the regular elevator operator lifts the handle 67 of said trip lever.

35 In Fig. 3 is shown a slight modification of the 50 invention which is in all general respects equivalent to that heretofore described except that here a single elevator door 250 is employed instead of the dual doors 24, 25.

I claim:

1. An elevator safety device comprising an elevator; an elevator well having a pair of oppositely opening doors; an elevator motor; a control cable adapted to be moved by one of said doors; means operatively connected with said cable and adapted to control the actuation of said elevator motor; and means actuated by said cable for locking the other door to said first named door.

2. An elevator safety device comprising an elevator; an elevator well having a pair of oppositely opening doors; an elevator motor; a control cable adapted to be moved by one of said doors; means operatively connected with said cable and adapted to control the actuation of said elevator motor; means actuated by said cable for locking said doors together when said doors are in their closed position; and manually operated means for unlocking said doors from each other.

3. An elevator safety device comprising an elevator; an elevator well having a doorway and

- a primary and a secondary door which move toward each other to close said doorway; an elevator motor; a control cable adapted to be moved by the opening of said secondary door; means operatively connected with said cable and adapted to control the actuation of said control motor; a dog pivotally mounted on said primary door; and a locking sleeve connected with said secondary door and adapted to be actuated by said cable to engage with said dog when the doors are in their closed position.
4. An elevator safety device comprising an elevator; an elevator well having a doorway and a primary and a secondary door which move toward each other to close said doorway; an elevator motor; a control cable adapted to be moved by the opening of said secondary door; means operatively connected with said cable and adapted to control the actuation of said control motor; a dog pivotally mounted on said primary door; a locking sleeve connected with said secondary door and adapted to be actuated by said cable to engage with said dog when the doors are in their closed position; and means for uncoupling said dog from said sleeve when the doors are to be opened.
5. An elevator safety device comprising an elevator; an elevator well having a pair of oppositely opening doors; an elevator motor; a control cable adapted to be moved by one of said doors; means operatively connected with said cable and adapted to control the actuation of said elevator motor; means actuated by said cable for locking said doors together when said doors are in their closed position; normal means for unlocking said doors from each other; and auxiliary means for also unlocking said doors from each other in an emergency.
6. An elevator safety device comprising an elevator; an elevator well having a pair of oppositely opening doors; an elevator motor; a control cable adapted to be moved by one of said doors; means operatively connected with said cable and adapted to control the actuation of said elevator motor; means actuated by said cable for locking said doors together; means located on the inside of one of said doors for unlocking said doors from each other; and auxiliary means located exteriorly of the elevator well for also unlocking said doors from each other in an emergency.
7. An elevator safety device comprising an elevator; an elevator well having a doorway and a primary and a secondary door which move toward each other to close said doorway; an elevator motor; a control cable adapted to be moved by the opening of said secondary door; means operatively connected with said cable and adapted to control the actuation of said control motor; a locking sleeve connected with said secondary door; means actuated by said cable for locking said sleeve to said primary door; and a lever fulcrumed on said primary door and adapted to unlock the same from the secondary door.
8. An elevator safety device comprising an elevator; an elevator well having a doorway and a primary and a secondary door which move toward each other to close said doorway; an elevator motor; a control cable adapted to be moved by the opening of said secondary door; means operatively connected with said cable and adapt-
- ed to control the actuation of said control motor; a locking sleeve connected with said secondary door; means actuated by said cable for locking said sleeve to said primary door; a lever fulcrumed on said primary door and adapted to unlock said primary door from said sleeve; means inside the elevator well for actuating said lever; and emergency means for actuating said lever exteriorly of said elevator well.
9. An elevator safety device comprising an elevator; an elevator well having a doorway and a primary and a secondary door which move toward each other to close said doorway; an elevator motor; a control cable adapted to be moved by the opening of said secondary door; means operatively connected with said cable and adapted to control the actuation of said control motor; a dog pivotally mounted on said primary door; a locking sleeve actuated by said cable and longitudinally movable a limited distance with respect to said secondary door and adapted to engage with said dog when the doors are in their closed position; and means for unlocking said dog from said sleeve.
10. An elevator safety device comprising an elevator; an elevator well having a doorway and a primary and a secondary door which move toward each other to close said doorway; an elevator motor; a control cable adapted to be moved by the opening of said secondary door; means operatively connected with said cable and adapted to control the actuation of said control motor; a locking sleeve actuated by said cable and connected with said secondary door; a pair of dogs mounted on said primary door at opposite sides of said sleeve and adapted to engage therewith when the doors are in their closed position; and means for simultaneously disengaging both of said dogs from said sleeve.
11. An elevator safety device comprising an elevator; an elevator well having a doorway and a primary and secondary door which move toward each other to close said doorway; an elevator motor; a control cable; means operatively connected with said cable and adapted to control said motor; a clip on said cable and adapted to be actuated by an opening movement of said secondary door; a sleeve connected with said secondary door and adapted to be actuated by said clip; a dog connected with said primary door and adapted to engage with said sleeve when said doors are in their closed position; and means for disengaging said dog.
12. An elevator safety device comprising an elevator; an elevator well having a doorway and a primary and secondary door which move toward each other to close said doorway; an elevator motor; a control cable; means operatively connected with said cable and adapted to control said motor; a clip on said cable and adapted to be actuated by an opening movement of said secondary door; a sleeve having a limited movement relatively to said secondary door and adapted to be actuated by said clip; a dog connected with said primary door and adapted to engage with said sleeve when said doors are in their closed position; and means for disengaging said dog.
